UNITED STATES PATENT OFFICE.

THOMAS HAWKSWORTH, OF ALLEGHENY, PENNSYLVANIA.

WASHING-MACHINE.

SPECIFICATION forming part of Letters Patent No. 272,250, dated February 18, 1883.

Application filed February 18, 1882. (No model.) Patented in England November 4, 1874, No. 3,808.

To all whom it may concern:

Be it known that I, THOMAS HAWKSWORTH, a subject of the Queen of England, residing at Allegheny, in the county of Allegheny and State of Pennsylvania, have invented certain new and useful Improvements in Washing-Machines, of which the following is a specification, reference being had therein to the accompanying drawing.

10 My invention relates to an improvement in washing-machines, it being the same invention for which Letters Patent were granted in England to Thomas Hawksworth and Joseph Chaffer, dated November 4, 1874; and it consists in the combination of the sliding gear-wheel, clutch mechanism, and gearing for operating the wringer, a cranked operating-shaft, rods loosely connected to the pounder at their lower ends, and to the shaft at their 20 upper ends, rods secured rigidly to the top of the pounder, and a guiding-plate which is secured rigidly to the rods on the pounder, and through the ends of which plate the operating-rods play when they are disconnected from the pounder, as will be more fully described hereinafter.

25 The object of my invention is to combine a wringer and a washing-machine in a single machine, in which the operating mechanism is so constructed that either one of the machines can be operated independently of the other.

30 The figure of the drawing shows a side elevation, partly in section, of a machine embodying my invention.

A represents the frame, provided with casters. Between the sides of the frame stands a cylindrical wash-tub, B, upheld by a gudgeon, upon which it rotates. In the frame, on 35 a line across the center of the wash-tub, is journaled the crank-shaft C, of which the ends protrude beyond the frame. On one of the protruding ends is geared the wheel W, provided with a handle, and on the other is the small toothed wheel a.

40 On the crank-shaft C are two rods, b, of which the lower ends are hooked in eyes on top of an oblong or oval box or case, D, that extends across the tub to near its sides without touch-

ing them. The case D is open at its under 50 side and its interior crosswise divided into compartments. As the box or case is loosely pivoted to the lower ends of the rods b for the sake of disconnecting it when it is desired to operate the wringer alone, it is necessary that there should be some means provided for holding the case or box always in position, so that it cannot turn on the rods. For this purpose the two rods c are rigidly secured to the top of the box, and have their 60 upper ends rigidly connected together by the plate or rod d, which has holes made through its extreme ends, so as to play freely on the rods b. As long as the pounder or case is being operated the rods b c and plate d 65 move with it, as if in one solid piece; but when it is desired to disconnect the box or case, so as to use the wringer alone, the connecting-pins are drawn out of the lower ends of the rods b, when the box at once sinks to 70 the bottom of the tub and remains stationary, while the rods b play freely through the plate d, which serves to keep the rods in a vertical position.

75 At the outside of the frame A, below and on a line with the wheel a, connected therewith by an endless chain or belt, is a larger wheel, E, on a shaft that has a small spur-wheel under the wash-tub, suitably geared with a circular toothed rim under the bottom 80 of the tub, causing it to revolve when the wheel W is in motion.

Over the crank-shaft, and journaled in the frame, are the rollers F F', the one over the other, the lower one, F, being geared with 85 wheel W, and the upper one, F', with F. The gearing of the roller F with the wheel W is such that when the crank-shaft is turned the roller remains idle, and, vice versa, when the roller is made to revolve the crank-shaft remains stationary. The roller F' is journaled in slots, so as to yield upward when required to prevent breakage, and is depressed by a spring, G, that is regulated by a set-screw, H, in the center of a brace, J, that unites the two 90 sides of the frame A. In front and rear, under the roller F, are removable shelves g.

95 The wheel W, when in motion and geared

with the crank-shaft, causes the case D to alternately ascend and descend while the tub containing the clothes slowly rotates.

I claim—

5 The combination of mechanism for operating alternately a wringer and washing-machine, consisting of the cranked shaft C, sliding gear-wheel W, clutch mechanism, gearing for operating the wringer, rods b, loosely cou-

nected to the box or case at their lower ends, to and guiding-plate d, substantially as shown.

In testimony whereof I have affixed my signature in presence of two witnesses.

THOMAS HAWKSWORTH.
